UNITED STATES PATENT OFFICE.

CLINTON C. EPPS, OF EUFAULA, OKLAHOMA.

COTTON-CLEANER.

1,090,606.

Specification of Letters Patent.

Patented Mar. 17, 1914.

Application filed December 23, 1912. Serial No. 738,196.

To all whom it may concern:

Be it known that I, CLINTON C. EPPS, a citizen of the United States of America, and a resident of Eufaula, in the county of 5 McIntosh and State of Oklahoma, have invented certain new and useful Improvements in Cotton-Cleaners, of which the following is a full, clear, and exact description, reference being had to the accompanying drawings, forming a part of this specification.

My invention relates to an apparatus for cleaning raw cotton before it is ginned, and by which the refuse is removed from the cotton.

The main object of my invention is to provide a cleaner of this kind by which what is known as boll cotton, that is, cotton which is left in the boll, when picked, may be removed from the boll and cleaned without cross breaking of the boll. Cleaners of the kind to which my invention relates usually include a beater and breaker bars, between which the boll cotton is crushed; and when 20 the bolls are acted upon between the beaters and breaker bars, the bolls are broken into fragments, resulting in the shale therein becoming reduced to particles which cling to the cotton and lessen its commercial value, 25 owing to the presence of the shale. My cotton cleaner is so designed as to obviate breaking of the shale in the cotton bolls in the process of opening them, and causing removal of the cotton therefrom and, as a 30 consequence, I am enabled to deliver the cotton from the cleaner free of the shale in the bolls.

A further object of my invention is to provide, in combination with a cotton cleaner of the description referred to a separator by 40 which the loose refuse in boll cotton may be extracted therefrom, previous to its entrance into the boll opening and cleaning chamber.

Figure I is a vertical longitudinal section 45 through my cotton cleaner. Fig. II is an enlarged vertical cross section.

In the drawings:—1 designates a delivery duct of a separator through which boll cotton is delivered to my cotton cleaner. This 50 delivery duct has two channels *a* and *b* therein, between which is a perforated wall 2. The boll cotton to be treated is forced or drawn through the channel *a* by air pressure or suction, and the loose refuse therein 55 is drawn through the perforated wall 2 by suction created in a suitable manner, as will

hereinafter more fully appear, and conducted away from the separator. In the channel *b* at the lower end of the perforated wall 2 are spaced slats 3, between which the refuse 60 passes, as indicated by the arrows Fig. I, after which it enters the suction duct 4 leading from the channel *b*.

5 designates the case within which the elements of my cotton cleaner proper are located, at the rear end of which is a suction outlet 6 that communicates with a refuse receiving duct 7, in which a draft of air may be occasioned by any suitable means; such, for instance, as a suction fan, having 70 suitable connection with said receiving duct. The refuse receiving duct is arranged for communication with the duct 4. A suitable gate 8 is provided at the junction of the ducts 4 and 7, and adapted to be moved into 75 various positions. For illustration, the gate may occupy an intermediate position, as illustrated in full lines, so that communication is maintained between the refuse receiving duct 7, and both the interior of the 80 case 5 and the duct 4; or the gate may be adjusted to one of the positions indicated in dotted lines to close communication between the duct 4 and the duct 7, thereby preventing communication between only the interior 85 of the case 5 and the refuse receiving duct, or adjusted into the other position indicated in dotted lines to prevent communication between the interior of the case 5, and provide communication only between the duct 4 and 90 the duct 7.

Within the case 5 is a perforated concave 9, preferably of coarse mesh wire fabric, this concave being suitably secured to the side walls of the case, and being of perforated 95 structure, in order that refuse may be drawn therethrough, into the chamber of the case 5, and therefrom into the refuse receiving duct 7, due to the draft maintained in said duct. In front of the case 5 is an elongated 100 eye or delivery opening 10, which extends to the front end of the perforated concave 9 at the bottom of said concave, and is preferably of the same width as the concave, so that boll cotton entering the cleaning chamber 105 designated "x" may be delivered to the concave in a thin layer extending throughout the width of the cleaning chamber; and, therefore, throughout the width of the concave. The boll cotton is conveyed to the eye 110 10 through a connection duct 11, which leads from the lower end of the separator duct 1,

and is constantly in communication with the channel *a* in said separator duct when my cleaner is in operation. At the front of the cleaning chamber "*x*" is a discharge opening 12, through which the cleaned cotton is delivered to a conveyer 13 to be conducted away from the cleaner.

14 designates a shaft mounted in the side walls of the case 5 adapted to be driven by power applied thereto in any suitable manner. This shaft constitutes a part of the beater of my cotton cleaner, the remainder of which comprises a plurality of arms 15 radiating from the shaft, that carry at their outer ends beater blades 16, each of a length corresponding to the width of the concave 9. The beater blades 16 are so arranged as to provide for their traveling in a circular path concentric with the concave 9; but always out of contact with such concave, though in close proximity thereto.

In the practical use of my cotton cleaner, the boll cotton freed of the loose refuse therein while passing through the separator duct 1 traverses the connecting duct 11 and passes through the eye 10 to enter the cleaning chamber "*x*" in a thin stream, or layer, as previously mentioned. This thin stream of boll cotton is drawn into the chamber "*x*" by the draft created through the concave 9 and spreads evenly over the concave. The beater of the cleaner being in operation, the cotton bolls are engaged between the beater blades 16 and the concave in a manner to mash or crush them without any breaking action, such as would break the shale in the cotton bolls. The beater is driven at a high rate of speed; and there being a multiplicity of the beater blades, opportunity is presented for a succession of blows, or impacts, by the beater blades against each and every boll passing along the surface of the concave 9, which forms a backing for the boll cotton while it is being subjected to the action of the beater blades. As the result, the cotton bolls are so treated as to efficiently open them without breakage, and free the cotton therein. The refuse or substance of the bolls passes, when the cotton is separated therefrom, through the perforated concave, due to the constant suction existing in the refuse receiving duct 7, and the cleaned cotton passes out of the cleaning chamber to the conveyer 13.

My apparatus may be used for separating loose refuse matter from cotton which is not contained in the boll, and in which instance it is unnecessary to pass the cotton through the cleaning chamber "*x*". To permit such use, I provide a gate 17 that is located at the lower end channel *a* in the separator duct 1. This gate occupies the position seen

in full lines Fig. I when the boll cotton cleaner is in service, thereby furnishing communication between the duct *a* and the connecting duct 11.

When the cleaner is not in service, the gate is adjusted to the position indicated in dotted lines, thereby cutting off communication between the channel *a* of the separator, and the duct 11, and permitting the cotton from which loose refuse has been separated to pass directly to the conveyer 13.

When my apparatus is in service for both separating the loose refuse from boll cotton and cleaning the boll cotton, the gate 8 is adjusted to the intermediate position shown in full lines Fig. I, thereby providing for the refuse from both the separator and the cleaning chamber being drawn into the refuse receiving duct 7; and, if the separator alone is used, the gate 8 is adjusted to the lowered position indicated in dotted lines, so that only the separator is in communication with the duct 7. By adjusting the gate 8 to the upper dotted line position, communication between only the cleaning chamber and the duct 7 is furnished.

I claim:—

1. In a cotton cleaner, a case having a separator duct 1 for the ingress of boll cotton, said separator duct having a perforated partition 2 subdividing it into a main channel *a* and a refuse channel *b*, a screen in said case, a breaker movable along said screen, a duct providing communication between said main channel *a* and the portion of said case in which said breaker is confined by said screen, a suction outlet duct adapted to receive the refuse passing through said screen, and a suction duct leading from said refuse channel *b* to said outlet duct.

2. In a cotton cleaner, a case having a separator duct 1 for the ingress of boll cotton, said separator duct having a perforated partition 2 subdividing it into a main channel *a* and a refuse channel *b*, a screen in said case, a breaker movable along said screen, a duct providing communication between said main channel *a* and the portion of said case in which said breaker is confined by said screen, a suction outlet duct adapted to receive the refuse passing through said screen, and a suction duct leading from said refuse channel *b* to said outlet duct, and a gate valve at the junction of the last named ducts operable to close either of said ducts and movable to permit said ducts to communicate with each other.

C. C. EPPS.
